UNITED STATES PATENT OFFICE.

EMIL L. JOHNSON AND OLOF LUNDSTEN, OF ATTLEBORO, MASSACHUSETTS.

BELT BUCKLE.

Application filed February 15, 1922. Serial No. 536,666.

To all whom it may concern:

Be it known that we, EMIL L. JOHNSON and OLOF LUNDSTEN, citizens of the United States, residing at Attleboro, in the county of Bristol and State of Massachusetts, have invented certain new and useful Improvements in Belt Buckles, of which the following is a specification.

This invention relates to new and useful improvements in the construction of separable belt buckles, and has for its object to provide a buckle of this character in which one end of a belt may be secured in adjusted position to the body portion of the buckle and the opposite end of the belt may be permanently secured to a separate member of the buckle which is adapted to be detachably connected to the body portion thereof whereby the buckle may be readily disconnected without interfering with its adjusted length.

With these and other objects in view, the invention consists of certain novel features of construction, as will be more fully described, and particularly pointed out in the appended claims.

In the accompanying drawings:

Figure 1 is a plan view illustrating the rear side of the body portion of our improved type of buckle showing one end of the belt as adjustably secured therein; also showing the separate connecting member as disconnected from the buckle and showing its attaching studs by which it may be readily connected to the body portion of a buckle.

Figure 2 is a sectional elevation on line 2—2 of Figure 1.

Figure 3 is a perspective view of our improved buckle.

Figure 4 is a perspective view in detail showing the detachable member of the buckle.

It is found in practice desirable to provide a buckle comprising a body portion having a front plate which is adapted to be suitably ornamented, and to provide in that body portion a clamp by which one end of the belt may be secured and to also provide another member of the buckle to which the opposite end of the belt may be permanently attached and to provide means in said member whereby it may be releasably secured to the body of the buckle by which construction the belt ends may be

separated without interfering with the adjusted length thereof after having been set to fit about the body of the individual wearer by which this result may be accomplished:—

With reference to the drawings, 10 designates the body portion of a buckle which is provided with a front plate 11 having rearwardly-turned edge walls 12 on either side thereof and these walls are preferably provided with inwardly-turned flanges 13 in which flanges are formed suitable slots 14, near one end of the buckle, having enlargements at one end as at 15 to receive the head portions of the studs, presently described.

At the opposite end of this buckle body we have turned inwardly the pair of tabs forming pivot ears 16 in which is mounted a clamp-bar 17 operated by a handle 18 to secure the end 19 of the belt in adjusted position in this body portion of the buckle.

In order to provide simple and effective means whereby the opposite end 20 of the belt may be secured to this body portion of the buckle, we have provided a so-called bail-member 21 which comprises essentially a plate having an opening 22 on its outer edge through which the end of the belt may be looped and secured by rivets 23, or otherwise, and this portion of the bail is provided with an enlargement or extension 24 which projects into this looped portion of the belt to guide the bail and prevent it from pivoting in the loop of the belt rendering it more readily operated when it is desired to connect this member to the body portion.

The inner face of this bail is provided with a pair of studs 25 which may be formed integral with the plate itself or they may be formed separate and riveted thereto and in either case each is provided with a shank portion having a head adapted to fit into the openings 15 in the flanges 13 of the body, and the shank portions of these openings so that when the heads are passed through the large opening and an endways tension is applied to the belt ends, the shank portions of these studs are drawn through the narrower openings 14 into the slightly enlarged ends 26 of the slots, the smaller portions of these slots 14 serving to slightly grip the shank portion of the studs and prevent them from accidentally

moving from their inner positions at 26 after having been drawn thereinto by endways tension on the belt.

In order to facilitate the positioning of 5 these heads in the holes 15 we have turned the surrounding wall portions inwardly as at 27 in Figure 2.

Our improved separable belt buckle is 10 very simple and practical in construction and effective in its operation and by its use the parts of the buckle may be quickly separated to remove the belt without interfering with the adjusted length of the belt when set to fit about the body of the wearer.

15 The foregoing description is directed solely towards the construction illustrated, but we desire it to be understood that we reserve the privilege of resorting to all the mechanical changes to which the device is 20 susceptible, the invention being defined and limited only by the terms of the appended claims.

We claim:

1. A separable belt buckle comprising a 25 body having a front plate with rearwardly turned edge walls said walls being provided

with inwardly-turned flanges having elongated openings therethrough, means in said body for binding one end of the belt in adjusted position therein, and a separate 30 bail member to which the opposite end of the belt is attached and means for engaging said flange openings by which its end of the belt may be releasably connected to the buckle body.

2. A separable belt buckle comprising a body having a front plate with rearwardly turned edge walls said walls being provided with inwardly-turned flanges having a pair of spaced apart openings therein, 40 means in said body for binding one end of the belt in adjusted position therein, and a separate bail member to which the opposite end of the belt may be attached and having a pair of cooperating inwardly-turned studs 45 adapted to enter said openings and to be drawn by a relative endways tension of the belt into locked position therein.

In testimony whereof we affix our signatures.

EMIL L. JOHNSON.
OLOF LUNDSTEN.
